LIFE PRESERVER

Frederick Lee Brown, Greenfield, Ohio, assignor
to The American Pad & Textile Company,
Greenfield, Ohio, a corporation of Ohio

Application August 7, 1943, Serial No. 497,745

5 Claims. (Cl. 9—17)

The present invention relates to life preservers and more particularly to life preservers of a vest or jacket type to be worn continuously by adults whose occupations or recreations impose upon them the hazard of drowning.

In several respects the present invention embodies certain features described in my Patent No. 2,331,301 and co-pending application, Serial No. 425,280 which are incorporated herein by reference to the extent that a better understanding may be had of the present invention.

The temptation is very strong with workers even at the risk of their lives to remove as a part of their wearing apparel a life preserver that encumbers their actions or tends to cause them to become unduly warm. In order to be adequately buoyant, a certain predetermined bulk of buoyant material has to be provided in life preservers according to government regulations, and this bulkiness which has to be disposed as high as possible on the chest of the wearer provides a critical problem.

In the present invention not only is the bulk of buoyant material required spread thinly, as discussed in the above-mentioned co-pending applications for the workers comfort and convenience, and the high center of effective buoyancy for the wearer maintained, but in addition to these, a life preserver is provided which is well ventilated and cool and can be readily handled by a boat hook or hand in event the wearer is found to be unconscious or helpless in the water. A further object of the invention is to provide for the ventilation of a life preserver in a new and improved manner over a large area of the wearer's back without sacrifice of a favorable buoyancy factor.

A further object resides in the provision of a life save vest which will withstand the strain of lifting a wearer out of the water regardless of where a boat hook engages the vest around the chest.

A further object of the invention resides in the provision of an improved life preserver embodying the features mentioned which is also reversible without changing or impairing the functions thereof, as described, regardless of how the vest is donned.

A further object of the invention is to preserve in a life preserver vest design the desirable feature of a universal size by which an adequate fitting is had for many adults regardless of height or weight so that a minimum number of sizes may be stocked as standard items for use by workers of varying heights and girths.

A further object of the invention resides in the arrangement of the required buoyant material in which the buoyant material allocated to the back section of the vest in several large pads, which are movable independently of each other horizontally, are located below the shoulders to rest against the ribs of the wearer at approximately the height of the shoulder blades.

A further object of the invention is to provide 10 a life preserver wherein the buoyant material is arranged around the chest of the wearer between vertical lines of stitching with openings through the vest for coolness and with the buoyant parts adjoining the openings serving more or less as guides for the point of a boat hook to facilitate its catching in the vest when necessity requires its use.

A further object of the invention is to provide 20 certain reinforcing strips which bound the upper ends of the openings between buoyant sections to preserve the shape of the life preserver and prevent any tearing thereof if a boat hook is used to lift the wearer from the water.

These and other objects of the invention will 25 become apparent from the drawings, the description relating thereto and the appended claims.

Referring to the drawings:

Fig. 1 is a front view of the preferred form of 30 the invention as it appears when fastened in place upon a person;

Fig. 2 is a back view of the vest shown in Fig. 1;

Fig. 3 shows the life preserver when it is unfolded and flattened;

Fig. 4 is a section taken upon the line 4—4 in 35 Fig. 3;

Fig. 5 is a section taken upon the lines 5—5 in Fig. 3;

Fig. 6 is a section taken upon the line 6—6 in Fig. 3; and

Fig. 7 is a diagrammatical view illustrating 40 the action of the life preserver upon the wearer when the wearer is in the water and a boat hook is being used to pull him out.

The life preserver is made up essentially of 45 three sections; the back section 10, and two symmetrically arranged front sections 11 and 12, either of which may be left or right, depending upon which side of the life preserver is next to the wearer's body. Each section is preferably 50 formed of two layers of suitable flexible covering material, such as a closely woven cotton cloth stitched together according to a predetermined pattern as will be described.

For convenience of description the two front 55 sections are referred to as having edges which

meet in front of the wearer and upper and lower portions 14 and 15, respectively, capable of folding against each other along a horizontal fold line.

The front sections are made of two superimposed layers of fabric 16 (Fig. 4) tapering and terminating at their upper edge as at 17 (Fig. 3) near the top of the shoulders and following down and around the arm 18 along the line 20 which is curved to circle the arm with comfortable clearance as at 21. A vertical slit is made in each front portion as indicated at 22, which slit extends downwardly to about the waist as at 23.

The side edges 13 and 20 and the edges along the slit 22 of the superimposed pieces of fabric are stitched together as at 26 to form a U-shaped envelope, which envelope is turned inside out and stitched along vertical lines 24 in the upper portion to form vertically disposed tubes 25 (Fig. 6).

A predetermined amount of buoyant material 9, preferably kapok, is then inserted in these tubes through the wide opening left at the bottom of the front section for that purpose. These tubes preferably extend down to approximately the waist line of the wearer and when the buoyant material is filled to this limit, a horizontal line of stitching 27 is made to close the tubes (Fig. 4). A second horizontal line of stitching, spaced from the first is then made across the front portion as at 28 to provide a horizontal tube 30 that bounds the bottom of the upper portions 14. Below the tube 30 the remainder of the front section is filled with a predetermined amount of buoyant material, preferably kapok, and the lower edge 31 is then closed by an inverted seam 32. This comprises the lower portion 15 and as thus formed is quilted by horizontal stitching such as that shown at 33 along one or more lines to predispose the lower portion to flex upwardly about the horizontal lines of stitching and the tube 30.

The rear portion 10 is made also of two superimposed layers 16a of fabric cut away at horizontally spaced points 34 to fit around the arm 18 at the back, over the shoulder, and under the arm to provide extensions 35 and 36 at opposite sides whose ends are adapted to be telescoped and secured by stitching to the front portions 12 at the top as at 37 and at the bottom as at 38. The back portion preferably terminates at its lower edge along the line 40 and is provided with a vertical slit 41 extending from the bottom thereof upwardly to a point 42 to provide two horizontally spaced pockets 43 (Fig. 5) separated by a vertically disposed opening 44 in which the end of a hook 45, such as that shown in Fig. 7, is received and directed upwardly toward the reinforcing element whereby the reinforcing element will carry the weight of the wearer. The outer marginal edges 46 of the back are stitched together except along the lower edge and the envelope thus formed is turned inside out and the horizontal line of stitching 47 made thereacross at approximately the upper end of the opening 44.

The two independent pockets 43 thus provided are then filled with a predetermined amount of kapok 9, in this case with all of the kapok that is allocated to the back section. The kapok is held in place by a horizontal line of stitching 48 spaced preferably a short distance from the lower edge. The lower edge is then closed with an inverted seam 50.

Although, for the sake of economy in cutting the material, it may be desirable to make the joining parts 35 and 36 over and under the shoulder separate from the back section 10, whatever

the pattern may be in this respect the outer edge of the parts extending over the shoulder are turned under to provide a smooth finish before the stitching 31 is completed.

Thereafter, a strip of heavy woven belting 51 is laid across the top of the vest with the ends 52 thereof extending well down along the slits 22 and stitched marginally in place as at 53 to form a reinforcing element over the shoulders, across the back, and around the neck of the wearer. This heavy belting serves a two fold purpose, namely, to provide a stiffening for the life preserver which makes it easy to handle, and a heavy reinforcement which is so arranged and anchored that the weight of the body of the wearer can be supported safely without the danger of the life preserver rending when upon occasions it becomes necessary to lift the wearer out of the water by the hook 45.

Where the joining part 36 of the back, which extends under the arm, engages the front portion, the front portion is left marginally open in the original stitching, which opening is closed by an inverted seam and a line of stitching 54 for securing to the front portion. This securing may be made either before or after the kapok is inserted in the front portion and it will be appreciated that the vertical lines of stitching 24 may be provided before the kapok is inserted in the upper part of the front portions or may comprise quilting stitches after the kapok is in place.

A tubular web-like portion 55 interconnects the two front portions along lines of stitching 56 as secured in place in a manner similar to that of the under arm parts 36, the tubular portion joining in open communication with the tubular portions 30 in both of the front portions, thereby providing one continuous tube from one edge of the life preserver to the other edge around the back to receive a draw-string or tape 57 therein which is secured by anchoring stitching 58 in the middle of the back. In order to anchor the back portion 10 under buoyancy and for lifting the wearer, and in order to prevent sagging of the tube 55 across the back, tapes 60 are stitched in place between the lower corners of the back portion and the tubular portion 55.

Across the bottom of the back portion and just under arm 18, the back and front portions 10, 11 and 12 are provided with a reinforcing tape 61 which ties the two parts of each front portion together at approximately the mid point of the vertical slits 22 therein in order to give the life preserver form and strength. Suitable hand ties are also provided along the meeting edges 13 of the front sections, such as the ones as shown at 63 which were secured in place as part of the original envelope assembly before the front sections 11 and 12 were turned inside out.

When the life preserver is donned by an adult, the life preserver can be immediately held in place for all practical purposes by fastening the draw tape 57. This draw tape gathers the vest around the torso of the wearer at approximately the waist with the material in the tube portion 55 across the back gathering along the tape to insure a snug fit regardless of the waistline of the user.

In confining a large portion of the buoyant material to the front portions, the buoyancy of the life preserver is such that the center of buoyancy is disposed well forward upon the body to tip it with the head back and face up as shown in Fig. 7. The lower portions 15 fold about the hori-

zontal lines of stitching 33 and about the draw tape 57 to raise the center of buoyancy as described in my co-pending applications.

The life preserver is also tailored to curve around the chest and arms in such a manner as to predispose the section to conform to the curvature of the body regardless of which side of the vest is out when it is put on. The vertical lines of stitching in the upper part of the front portion permits the life preserver to fit snugly around the ribs of the wearer while the horizontally disposed lines of stitching in the bottom portion and at the waist permit the lower portion to yield either to buoyancy or to the action of the torso and legs when upon occasion the wearer stoops over or sits down. Moreover the marginal stitching and turning of the three sections insideout before filling them with kapok, provides smooth and rounded edges at the margins of these respective sections as shown in Fig. 6, whereby the fabric is rounded out to provide for the maximum capacity of kapok.

Furthermore, the slits in the front and back portions of the vest are free of obstruction to permit the end of a boat hook to slip between them readily and to engage the reinforced portions of the vest so that the wearer can be handled with a boat hook or by hand upon occasion. Moreover, by slitting the front and back portions the buoyant portions which press against the body due to the fit of the life preserver are permitted to move with the body rather than resist movement of the body of the wearer. Thus, a more comfortable life preserver is provided along with the ventilation of the body, to the end that the life preserver is much cooler to wear in summertime than conventional life preservers.

In the foregoing description it will be noted that reference has been made to a predetermined amount of buoyant material being placed in the respective pockets or tubular constructions of the vest. Kapok is shown and described herein as the preferred buoyant material because of its lightness, flexibility, high buoyancy and softness, but the invention contemplates the use of any buoyant material which is by nature or necessity an acceptable substitute for kapok, and the context herein is to be so construed. Although a few pounds displacement is all that is normally required to support a person in the water, it is considered desirable to have within the jackets sufficient buoyant material to support approximately 16 pounds dead weight for 48 hours of immersion. The amount of material therefore required will depend upon the specific gravity, the water absorption, and other characteristics of the buoyant material employed. It is preferred in this connection to employ kapok as a buoyant material since it has been found to be the most suitable material for this purpose and a total of 20 ounces of kapok disposed in the manner described is ample to support the test weight, as required. It is also preferable for the purposes of the present invention that the quantity of kapok disposed in the front and shoulder sections of the vest be at least twice the amount of that disposed in the back section in order that the center of buoyancy will not only be relatively close to the wearer's shoulders, but also near the chest side of the wearer as has already been mentioned. With this arrangement the life preserver will, at all times, tend to keep the chest up and the head back to assist in the hook 45 catching in the life preserver quickly.

Moreover, it will be of interest to note that the padding is so located that it will cushion the force of a rapidly moved boat hook in most cases unless the boat hook happens to engage in the slot on the first thrust, the pads of buoyant material also serving as projections which not only direct the boat hook into its proper place, but provide projections by which the wearer's body can be manipulated with the boat hook to turn it around for an advantageous hold by the boat hook.

Consequently, although several modifications may be made in the structure as described, it will be appreciated that various and further changes can be made as regards cutting the life preserver to patterns for economy's sake without departing from the spirit of the invention, the scope of which is commensurate with the appended claims.

What is claimed is:

1. A life preserver tailored to be worn as a vest comprising two buoyant front sections divided into vertically spaced buoyant portions secured with respect to each other by fabric and adapted to fold into overlapping contact with each other when submerged in water, a reinforcing element interconnecting the tops of the front sections across the back of the wearer, a pair of buoyant back sections supported below said reinforcing element, said buoyant sections defining therebetween a vertical slit terminating adjacent to and below the reinforcing element whereby a hook inserted between said buoyant elements is directed upwardly toward said reinforcing element, and means for securing the back section against the wearer's body at approximately the waist including an element drawing the front sections inwardly between the upper and lower portions.
2. A life preserver tailored to be worn as a vest comprising two buoyant front sections divided into vertically spaced buoyant portions adapted to fold along a horizontal line into overlapping contact with each other when submerged in water, said upper portions being split along a substantially vertical line extending downwardly to approximately the fold line, a back buoyant portion, reinforcing belting extending over the shoulders of the wearer, said belting being secured to the back portion, and to the front portions in a manner bridging the splits, means for holding the front portions against the wearer's body at the fold line including open work webbing interconnecting the front sections and back section across the back and a draw element.
3. A life preserver tailored to be worn as a vest comprising two buoyant front sections adapted to meet in front of the wearer, said sections comprising superimposed layers of fabric marginally fastened to define envelopes filled with a buoyant material held in place along vertical lines in the upper portion and horizontal lines in the lower portion of each section, said sections having a vertically extending opening through the fabric for ventilation in the upper portions, a buoyant back section, means for securing the back section to the front sections over the shoulders and under the arms of the wearer above said lower portions including open work webbing affording ventilation and a draw element for holding the buoyant sections against the wearer's body at the waist between said upper and lower portions and predisposing the lower portions to fold into overlapping contact with the upper portions under the influence of buoyancy.
4. A life preserver tailored to be worn as a vest comprising two buoyant front sections divided

into vertically spaced buoyant portions capable of folding into overlapping contact with each other along a horizontal fold line, the upper part being divided by a vertically disposed cut, a buoyant back portion connected to the side edges of the front portions at vertically spaced points to define arm holes, said rear portion being divided by a vertically disposed cut, a reinforcing member extending across the top of the back portion above the vent and secured at its ends to the tops of the front portions, and means for securing the life preserver upon a wearer including a tubular member interconnecting the front portions across the back at approximately the waist and a draw element in the tube fastened to the tube at the back.

5. A life preserver tailored to be worn as a vest comprising two buoyant front sections divided into vertically spaced buoyant portions capable of

10 folding into overlapping contact with each other along a horizontal fold line, the upper part being divided by a vertically disposed cut, a buoyant back portion connected to the side edges of the front portions at vertically spaced points to define arm holes, said rear portion being divided by a vertically disposed cut, a reinforcing member extending across the top of the back portion above the vent and secured at its ends to the tops of the front portions, a second reinforcing element extending around the vest below the arms of the wearer and spanning the cuts in the front portions, and means for securing the life preserver upon a wearer including a tubular member interconnecting the front portions across the back at approximately the waist and a draw element in the tube fastened to the tube at the back.

FREDERICK LEE BROWN.
